US00D597050S

(12) **United States Design Patent**
Kim et al.

(10) **Patent No.:** US D597,050 S
(45) **Date of Patent:** ** Jul. 28, 2009

(54) **MOBILE PHONE**

(75) Inventors: **Kang-Moon Kim**, Seoul (KR);
Young-Ju Yeo, Seoul (KR); **Chang-Soo**
Lee, Incheon (KR)

(73) Assignee: **Samsung Electronics Co., Ltd.**,
Suwon-Si (KR)

(**) Term: **14 Years**

(21) Appl. No.: **29/320,787**

(22) Filed: **Jul. 3, 2008**

(30) **Foreign Application Priority Data**

Mar. 19, 2008 (KR) 30-2008-0011799

(57) **CLAIM**

The ornamental design for a mobile phone, as shown and described.

DESCRIPTION

FIG. 1 is a front perspective view of a mobile phone;

FIG. 2 is a front view of the mobile phone of FIG. 1;

FIG. 3 is a rear view of the mobile phone of FIG. 1;

FIG. 4 is a left-side view of the mobile phone of FIG. 1;

FIG. 5 is a right-side view of the mobile phone of FIG. 1;

FIG. 6 is a top plan view of the mobile phone of FIG. 1; and,

FIG. 7 is a bottom plan view of the mobile phone of FIG. 1.

1 Claim, 5 Drawing Sheets
